UNITED STATES PATENT OFFICE.

GUSTAV GNAM, OF BROOKLYN, NEW YORK, ASSIGNOR TO AUTO-AUTOMATIC SIGNAL CO., INC., OF BROOKLYN, NEW YORK, A CORPORATION OF NEW YORK.

AUTOMOBILE REAR SIGNAL.

Application filed February 11, 1921. Serial No. 444,175.

To all whom it may concern:

Be it known that I, GUSTAV GNAM, a citizen of the United States, and residing at 2202 Tilden Avenue, Brooklyn, in the county 5 of Kings and the State of New York, have invented certain new and useful Improvements in Automobile Rear Signals, of which the following is a specification.

This invention relates to improvements in 10 signal devices for automobiles and particularly to that class of such devices which give a signal to the traffic in the rear, to indicate the proposed movement of the vehicle provided with the signal by means readily operable by the foot of the driver.

It is the object of the present invention to provide a device which is absolutely reliable in its operation and remains unaffected by the constant vibrations of the car.

20 It is another object of the invention to provide controlling means to inform the driver that the device has carried out the desired function properly.

A further object of the invention is the 25 simplification of the attachment of the switching means to the car and particularly to the operating pedals. With these and other objects in view the invention consists in certain novel details of construction and arrangements of parts hereinafter described and set forth in the appended claim.

Reference is to be had to the accompanying drawings in which:

Fig. I is a sectional elevation of the signal 35 showing a part of the front of the casing. The panels, 12, 18 and a part of 17 are removed from their holding arms to show the mechanism behind them.

Fig. II, is a sectional plan of the signal 40 on the line II—II of Fig. I.

Fig. III is a sectional side elevation taken on the line III—III of Fig. I.

Fig. IV, is a wiring diagram of the signal.

45 Fig. V, is a plan view of the pedal-switch.

Fig. IV is a sectional elevation on the line VI—VI of Fig. V.

Fig. VII is a side elevation of Fig. V.

50 Fig. VIII is a detail showing the relay contact 21 and resilient top of one of the armatures.

Referring to Figs. I to III of the drawing the signal device is mounted on a vertical plate 1 which holds on its rear side a suitable bracket 2 providing means for its attachment to the car. To the front side of plate 1 are fastened three vertical solenoids 3—4—5 in symmetrical arrangement in and about its vertical centre line. These solenoids are provided with the armatures 6—7—8. The lower ends of these armatures are slotted to form a fork which holds by means of the pins 10 in hinged connection suitable arms, preferably shaped from sheet metal. The shape of these arms can best be seen in Fig. II. Solenoid 4 by means of armature 7 carries bracket 11 in central alinement on plate 1. The arm is bent in such a manner that an upwardly directed part of it extends parallel to plate 1, to this part a rectangular panel 12 is fastened, also parallel to plate 1. The vertical edges of this panel are guided in U-shaped guide channels 13 which are supported near their top and bottom ends in apertures of angularly bent brackets 16 suitably fastened to plate 1. Similar guide channels 14 and 15 are arranged parallel to 13 in the same brackets 16, they guide the panels 17 and 18 which are carried by means of bent arms 19 and 20 by armatures 6 and 8 and operated by solenoids 3 and 5 respectively; it will be noticed that arms 19 and 20 are bent to pass through the spaces between guide-channels 13—14 and 14—15. (See Fig. II.) Above 55 each one of the solenoids 3, 4, 5 and in the path of their armatures a contact point 21 is mounted in a bracket 22 held on plate 1 as shown in detail by Fig. VIII. The upper part of the armatures (6) is bored out to form a tube 60 in which a piston 61 is slidably held supported by a helical spring 62. The upper part of the piston is slightly reduced in diameter to form a shoulder which forms a stop for its upward motion on the 60 inwardly bent edges of tube 60. In their lowest position the armatures 6, 7, and 8 rest on brackets 23 which are also held on plate 1. The whole signal device is enclosed in a casing 24 provided with a window opening 25 through which the sign panels are made visible. The casing 24 is provided in 65 70 75 80 85 90 95 100

its central upper part with a lamp socket 26 for the rear light 27 which is protected by a hood 28 forming a part of the casing which holds the glass lens 29. When nuts 30 and bolts 31 hold the casing 24 on plate 1 they are so arranged that a license plate 32 may be clamped to the face of the casing.

In Figs. V—VI and VII details of a push button switch 40 are shown. Two of such switches are attached to the side edges of the 10 brake pedal 41 and one to the clutch pedal 42 as indicated in Fig. IV. Each push button switch consists of a body part 40 which is preferably attached by a single screw 43 to the pedal plate 41. The switching mechanism proper consists of a button 44 provided with a vertical stem 45 flared out at its base and held in an aperture of a box like extension of body 40 which is held close to the 20 edge of pedal plate 41. Button 44 is pushed upward by means of helical spring 46 which surrounds stem 45 and is lodged in a counterbore of a cylindrical extension 49 extending upwardly from body 40 into an annular 25 recess of button 44. To the bottom surface of 40 a block 47 is fastened, insulated therefrom, which carries the binding screw 48 to hold the conducting wire.

The operation of the signal is as follows: 30 Should the operator of the automobile wish to turn his car to the left, he will shift his foot on the clutch pedal 41 slightly to the left and touch button 44 of switch 40 marked "L" on Fig. IV closing the same, as the 35 flared base of 45 (see Fig. VI) will touch block 47 making contact therewith, current will then pass from the ground through coil 3 lifting armature 6 with arm 19 and sign panel 17 having the inscription "Left" thereon attached to that arm. From coil 3 the 40 connection leads to the storage ignition battery and from that to the body of the car as ground connection. When armature 6 is lifted to its highest position and the sign 45 panel is displayed in the window opening, it will strike the insulated contact point 21 forming a connection of the same with the ground, from this point current will pass through a pilot lamp marked "L" held with 50 two similar ones in a suitable housing on the dashboard of the car and from there through the battery to the ground. In the same manner the two other armatures with their respective sign panels may be operated and in 55 each case a pilot lamp will light up as soon as the particular panel is fully lifted. The lamp 27 which serves as a rear light for the car remains always in the circuit and it is arranged to illuminate the sign panels.

60 The present invention embodies various novel features which assure a proper functioning of the signal device and which are improvements over similar devices previously constructed, embodying the principle

of lifting sign panels by means of solenoids. 65 In the present device these sign panels are all arranged in front of a series of solenoids and the weight of the panels inclusive of that of the carrying arms is balanced about the pin 10 in the lower part of their respective armatures, which insures a free and easy moving of their vertical edges in the channel guides 13—14—15.

Another improvement is to be found in the manner of operating the pilot lights by 70 means of a relay circuit which is closed only when the sign-panel to be displayed has actually reached its proper position, in this manner the driver of the car receives the positive assurance that the sign is displayed 75 by seeing the pilot lamp lighted and in case of a failure for any reason, he is able to give a manual signal to a car in the rear. The resilient mounting of the contact points in the armatures is an improvement of particular 80 value to insure a reliable contact and to permit slight vibrations of the signal-panels without extinguishing the pilot lamp. In place of pilot lights a magnetically operated 85 annunciator might of course be used. In devices where pilot lamps are arranged in the operating circuit there is no assurance 90 that the mechanical part of the device has operated properly, although the pilot lamp 95 may be lighted.

The push-button switches, their attachment to the pedals and their particular construction for the functions they have to perform, are also novel features of the invention. In devices heretofore placed on the 100 market, the whole pedal plate was of special construction to perform the switching operation, while in the present device small switches are attached to the existing pedal plates of any car by means of a single 105 screw. These switches are so designed that they do not occupy any space on the top of the pedal-plate, excepting a thin connecting plate. Provision is made that no dirt or 110 foreign matter can enter the switching mechanism, or interfere with its operation. This is effected by means of the projecting ring 49 which enters the annular recess in button 44 and keeps the device closed at all times. The vertical movement of button 44, required to close the switch is considerably 115 shorter than the space between the underside of 44 and body 40, that any foreign matter accumulated at that place may not interfere with the operation of the switch.

Having thus described my invention, what I claim as new and desire to secure by Letters Patent is:

120 In a signaling device of the kind described a casing having parallel front and rear plates, a plurality of solenoids held near said rear plate at its central portion, an armature for each solenoid, sign plates adapt-

ed to slide vertically in guides held in said casing between the planes of said solenoids and said front plate, a window in said front plate opposite said solenoids, a horizontal arm for each sign plate extending through a space between two adjacent guides to its sign plate rigidly fastened thereto at one of its ends to hold said plate in balanced condition the other end of each arm being held at one of said armatures to be lifted thereby and to display its sign plate within said window. 10

GUSTAV GNAM. [L. s.]
